FLUID LIFT

Sanford C. Brady, deceased, late of Bartlesville,
Okla., by Nelson G. Brady, administrator,
Bartlesville, Okla.

Application September 12, 1944, Serial No. 553,762

6 Claims. (Cl. 103—234)

This invention relates to a fluid lift and it is an object of the invention to provide a device of this kind which is automatic in its operation and which provides an efficient and economical means of lifting fluid from oil and gas wells and other shafts.

Furthermore, it is an object of the invention to provide a device of this kind which can be operated on either high or low pressure.

The invention consists in the details of construction and in the combination and arrangement of the several parts of the improved fluid lift whereby certain important advantages are attained, as will be hereinafter more fully set forth.

In order that the invention may be better understood, the same is now described with reference to the accompanying drawing, wherein:

Figure 1 is a view partly in elevation and partly in section illustrating a fluid lift constructed in accordance with an embodiment of the invention;

Figure 2 is an enlarged sectional view taken substantially on the line 2—2 of Figure 1; and

Figure 3 is an enlarged detailed sectional view taken substantially on the line 3—3 of Figure 1.

As disclosed in the accompanying drawing, 1 denotes an elongated barrel of desired dimensions and which has its lower end closed by a plug head 2, said head 2 having a reduced portion 3 which threads within the barrel 1. This plug head 2 has disposed axially therethrough an inlet port 4, the inner or upper extremity of which is enlarged to provide a seat 5 for the ball valve 6.

The lower or outer portion of the opening or port 4 is enlarged, as at 7, and threading within said enlarged portion 7 is an extremity of a fluid inlet member 8 provided in its wall at spaced points therearound and therealong with the fluid inlet ports 9.

Threading within or otherwise effectively engaged with the upper end portion of the barrel 1 is a second plug head 10 having a relatively large central opening 11, the outer portion of which is enlarged, as at 12, to receive the packing 14 with which coacts in a well known manner a gland ring 15 for expanding the packing 14.

In the present embodiment of the invention, the packing ring 15 is forced inwardly against the packing 14 by a cap nut 16 threading upon the outer portion of the plug head 10 and having a central opening 17 through which freely passes the lower portion of a fluid outlet pipe 18 of desired dimensions.

This lower extremity of the pipe 18 extends within the upper portion of the barrel 1 through

the opening 11 in the plug head 10 and the portion of the pipe 18 within the enlargement 12 of the opening 11 is tightly surrounded by the packing 14, whereby a fluid-tight joint is assured yet allowing for relative movement between the barrel 1 and the pipe 18 as a direction lengthwise of the pipe 18.

In the present embodiment of the invention, the barrel 1 comprises two sections x and y having their opposed or inner ends spaced apart a desired distance and with said opposed ends of the sections x and y connected by a coupling plug 19 threading within the opposed end portions of the sections x and y, as is clearly illustrated in Figure 3 of the drawing.

The lower section y of the barrel 1 in its upper portion is intersected by a plate 20. This plate 20 is spaced from but in relatively close proximity to the adjacent end of the coupling plug 19 and is held in place by the suitably positioned binding screws 21 or otherwise as may be preferred. This plate 20 is provided therethrough with a suitably positioned port 22 affording communication with the section y of the barrel 1 at opposite sides of the plate 20.

Threading through the plate 20 at its axial center is a shank 23 which constitutes an adjustable stop for the valve 24. This valve 24 coacts with the valve seat 25 surrounding the lower end portion of a port 26 disposed axially through the coupling plug 19.

The valve 24 is carried by a stem 27 which is of a major diameter materially smaller than that of the port 26 and which is of a length to extend 35 a material distance upwardly beyond the coupling plug 19 and within the upper section x of the barrel 1. The stem 27, however, tightly but slidably passes through a nipple sleeve 28 which threads from above within the upper portion of 40 the port 26 and which is provided at the axial center of the lower head 29 for the bellows 30.

The coupling plug 19 has radially disposed therethrough a port 31 leading from a point between the opposed ends of the sections x and y 45 of the barrel 1 and in communication with the central portion of the port 26.

The top head 32 for the bellows 30 has its central portion suitably fixed, as at 33, to the adjacent upper end portion of the stem 27. Interposed between the head 32 of the bellows and the inner or inserted face of the plug head 10 50 is an expandable member 34 of requisite tension and herein disclosed as a coil spring.

Threading upon the lower end portion of the pipe 18 within the section x of the barrel 1 is an

adjustable stop flange 35. This flange 35 determines the extent of relative movement in one direction between the barrel 1 and the pipe 18.

The upper end portion of the pipe 18 extends up through an opening 36 in the central bottom portion of the aspirator housing 37. The bottom 38 of the housing 37 is disposed on a downward and inward taper to the central opening 36 to provide an upwardly facing internal valve seat 39.

Coacting with this valve seat 39 is an annular beveled face 40 carried by the lower portion of a cup head 41 threaded or otherwise mounted upon the adjacent upper end portion of the pipe 18 and with which said pipe 18 communicates from below. The wall of this head 41 is provided therearound with the perforations 42.

The housing 37 has its normally open upper or top face closed by a cap head 43 and which cap head 43 freely receives the cup head 41 as the periphery of said head 41 is spaced from the wall of the applied cap head 43, as is clearly illustrated in Figure 2 of the drawing.

Extending through the central portion of the cap head 43 and in threaded or other desired connection therewith is the lower extremity of a second fluid outlet pipe 44 of desired length and which extends through and above the head 45 which seals the upper end of the well casing 46.

Fixed to the pipe 18 at a desired distance above the head 45 and surrounding the same is a disk plate 47 through which are threaded at spaced points therearound the jack screws 48 which contact with and bear upon the head 45 from above, said screws being located in their desired adjustments in a conventional manner by the nuts 49 or otherwise as may be preferred.

The upper extremity of the outlet pipe 44 is continued by the pipe 50 leading to a suitable point of discharge.

In the present embodiment of the invention, the desired gas pressure is obtained within the well although, if desired, the applied pressure may be obtained from an outside source. However, as this is of no particular importance insofar as the invention herein embodied is concerned, a detailed showing as to any outside source of pressure is believed unnecessary.

When the device is installed in the well or casing 46, the face 40 is in engagement with the valve seat 39 under the influence of the weight of the pipe 18 and the parts carried thereby. When the inlet member 8 comes to rest upon the bottom of the well and the pipe 44 is further lowered slightly, the face 40 will separate from the seat 39. Also, the down movement of pipe 18 compresses spring 34 and bellows 30, causing valve 24 to unseat or open. This allows the gas from the well, either the natural gas or introduced gas, to flow through the aspirator A which tends to pull the liquid up through pipes 18 and 44 by way of the inlet port 31. Such fluid movement will, of course, be assisted by the pressure tending to force the liquid in through port 31. By these means the fluid is permitted to flow until the fluid in the well is lowered to the port 31. It is desirable, when the device is permanently installed, to have the port 31 just above the fluid level *a* to admit well pressure during the operation of the pump and yet to allow for sufficient liquid submergence to assure maximum flow of fluid out through the pipe 18 to assure the desired lifting of the fluid column to the surface. After the fluid is lowered to port 31 the member 18 is adjusted by adjusting the jack screws 48, so that the entire assembly is lifted off the bottom of the well and the weight of the pipe

18 and the parts carried thereby will return the face 40 to the seat 39 which will also result in a decrease in the tension of the spring 34 which results in decreasing pressure on the bellows 30 so that the valve 24 will close against its seat 25.

Fluid then comes up by way of pipe 8, past valve 6 and through ports 22 and 52, through the upper section *x* of the barrel 1, and rises up in the column through the outlet pipe 18 to a sufficient height which, in conjunction with the tension of the spring 34, will compress the bellows 30, causing the valve 24 to open. The opening of the valve 24 will admit the well gas under pressure to the column through the port 31 and at the same time cause the valve 6 to close on its seat 5, stopping the flow of fluid into the barrel and boosting the column of fluid in pipe 18. As the fluid rises in the pipe 18 prior to the opening of the valve 24, the external pressure on the bellows 30 resulting from weight of the flowing column, together with the tension of the spring 34, has been placing the bellows 30 under compression.

As soon as the bellows 30 opens slightly, gas pressure from the well is admitted, resulting in a still greater compression of the bellows 30, thereby opening wide the valve 24 and allowing the well gas to force the fluid column to the surface. Since the fluid column seals off this pressure until the column is discharged at the surface at substantially atmospheric pressure, the bellows remains under compression until the instant of such discharge, at which time the pressure suddenly drops. With this drop in pressure, the bellows under compression instantly expands, closing the valve 24, and since the pressure within the barrel 1 is less than well pressure, the fluid under well pressure will lift the valve 6 off its seat 5, whereupon the cycle of operation will be repeated.

The aspirator A, as particularly illustrated in Figure 2 of the drawing, is only used in installing the pump at proper level in a well, although in a very shallow well such use will not be necessary since a spray of liquid could be carried to the top of the well by vapor coming through the port 31. However, in deeper wells, this aspirator A boosts the liquid carried up from the bottom to the surface.

While in the accompanying drawing only a single aspirator is shown, it is believed to be obvious that if the requirements of practice should so necessitate, additional aspirators may be employed to assure the lifting of the fluid to the surface.

From the foregoing description it is thought to be obvious that a fluid lift constructed in accordance with my invention is particularly well adapted for use by reason of the convenience and facility with which it may be assembled and operated.

What is claimed is:

1. An apparatus for lifting fluid comprising a barrel divided into an upper chamber and a lower chamber, the lower chamber having an inlet port in communication therewith, a valve for preventing retrograde flow through the inlet port, said barrel having a port in communication with the two chambers and with a pressure inlet port in communication with the lower chamber, a valve for controlling flow through the pressure port, a bellows within the upper chamber of the barrel and operatively engaged with the valve for controlling flow through the pressure port, means actuated by the weight of the apparatus resting upon an underlying support for adjusting pressure on the bellows, and an outlet pipe in com-

munication with and leading from the upper chamber of the barrel.

2. An apparatus for lifting fluid as set forth in claim 1, wherein the barrel is slidably mounted upon the end portion of the outlet pipe in communication with the barrel.

3. An apparatus for lifting fluid as set forth in claim 1, wherein the means for exerting pressure on the bellows comprises an expansible spring interposed between the bellows and the upper head end of the barrel.

4. An apparatus for lifting fluid as set forth in claim 1, wherein a plate is mounted within and intersects the lower chamber of the barrel and is provided with a port, and means carried by the plate for coaction with the valve for controlling the flow through the pressure port to limit the extent of opening movement of such valve.

5. An apparatus for lifting fluid as set forth in claim 1, wherein means are interposed in the outlet pipe above the barrel to facilitate the lifting of the fluid column through the outlet pipe.

6. An apparatus for lifting fluid as set forth in claim 1, wherein the outlet pipe comprises two sections, a casing carried by an end portion of one of the sections and the second section extending within the head, said head and the portion of the second section within the head being provided with a coacting valve and valve seat whereby well pressure may be admitted within the upper section of the outlet pipe upon relative movement of the sections of the pipe to unseat the valve of one of the sections.
